SHIP'S SIGNALING SYSTEM

Robert Rodger Glen, Anglet, France, assignor to
 Glen's Patents and Holdings, Inc., New York,
 N. Y., a corporation of Delaware

Application March 27, 1935, Serial No. 13,243
 In Great Britain September 22, 1934

8 Claims.

(Cl. 179—1)

This invention relates to improvements in ships' signaling systems and more particularly to ships' telephone systems, and has for its object generally to provide means for ensuring the transmission and reception of communications on board ship from a control point, such as the bridge, to stations on the ship.

There are occasions when a ship at sea or the ship's company encounters grave danger, for example, by reason of storm, collision, fire, icebergs, mutiny, action of an enemy, or other disaster. In such circumstances, and especially on large vessels carrying many people, the danger is greatly increased if panic and disorder develop; but, on the contrary, the chances of saving life and property and, generally speaking, the chances of overcoming the danger are greatly increased if a commanding authority, such as the master of the ship, can ensure the reception of his orders at stations throughout the ship.

Loudspeaking telephones are in use in service ships, but in most instances, these are appropriated to ordinary telephone communication from one person to another. It is also known, particularly on passenger ships undertaking pleasure cruises, to use the phonograph or radio loudspeakers for making announcements.

A specific object of the present invention is to provide apparatus of a foolproof character to be installed permanently on a ship as part of its equipment to enable one in command at a control point to convey oral messages to stations at different parts of the ship so that at those points the messages will be reproduced or emitted in a penetrating manner. In the practice of the invention, a loudspeaker installation is provided on board a ship which generally includes a microphone located at a control point of the ship (for example, the bridge), an amplifier in a suitably protected situation, a connecting electrical network leading to selected stations on the ship to which it may be necessary to transmit orders from the control point (for example, the boat stations) and loudspeakers capable of sufficient output to be heard above the noise associated with a storm, panic, or other disturbance, secured at such stations.

Experiments with sound reproducing instruments of the general type referred to have shown that instruments of a highly penetrating quality are desirable for systems provided in accordance with the invention. It has been found that loudspeakers constructed in accordance with that disclosed in my copending application, Patent No. 2,071,828, issued February 23, 1937, have the

desired penetrating quality and are therefore preferred.

A loudspeaker, according to my said copending application, suitable for a ship's signaling system of the present invention, should have a sound cone of relatively wide angle, for example, in the neighborhood of 178 degrees, in order to withstand the better the effects of wind and rain. Both the driving and the driven cones are preferably made of metal and in size are of from six to eight inches in diameter while the distance between them is made relatively small, for example, 3/64ths of an inch.

Other objects of the invention will in part be obvious and will in part appear hereinafter.

The invention accordingly comprises the features of construction, combination of elements, and arrangement of parts, which will be exemplified in the construction hereinafter set forth, and the scope of the invention will be indicated in the claims:

For a fuller understanding of the nature and objects of the invention reference should be had to the following detailed description taken in connection with the accompanying drawings, in which:

Fig. 1 is a diagrammatic side view of a ship showing the location of the various elements and the wiring arrangement;

Fig. 2 is a plan view of the bridge;

Fig. 3 is a view of the bridge looking forward;

Fig. 4 is a section of one form of loudspeaker; and

Fig. 5 is a diagrammatic view showing an exemplary wiring diagram of an electrical network suitable for the practice of the invention.

Referring now to the drawings, a ship is indicated having a bridge on which is secured a microphone 1 at a position convenient to the officer in command, viz., fixed in the wall of the bridge adjacent to a centrifugal port 2. Adjacent to the microphone is a switch 3 which may, by means of a known form of lock, be under the sole control of the officer in command. The microphone is connected by means of a suitable electrical network to an amplifier 4 preferably disposed in a central protected position, such as the radio room. A second amplifier 5 for alternative or emergency use may be provided, if desired, and located in the gyro room of the ship. The electrical connections have outlets available to loudspeakers of the kind later described secured at desired stations (i. e., groups of stations) over the ship. Such stations may be, for example,

- (1) Lookout stations as shown at 6 and 7;
- (2) Boat stations 8, 9, 10, 11, and 12;
- (3) Engine and boiler rooms 13 and 14; and/or
- (4) Night watchman and crew's quarters 15

5 and 16.

The switch 3 at the control point is a distributing switch by which, at the will of the officer in control, the microphone and amplifier may be put into communication with all stations at once or with one or more selected stations. The microphone and switch assembly may, if desired, be duplicated; thus there may be one microphone and switch assembly at each wing of the bridge and each of these may be arranged to be connected at will through one wiring system to the amplifier and loudspeakers.

An additional microphone and switch assembly 17 for emergency use are fixed adjacent to the after binnacle and both microphones are connected by alternative systems of wiring to the amplifiers and to the loudspeakers. The wiring systems are indicated in chain lines and in dot-and-dash lines respectively in Fig. 1, and are preferably spaced apart in the ship in order 25 to lessen the risk of simultaneous damage to both systems.

It is important that the equipment throughout should be, so far as possible, free from the risk of interference by fire or other accident. 30 Therefore, the electrical conductors are suitably concealed and are insulated by fireproof insulation and/or contained in fireproof sheaths or channels.

In the wiring diagram, shown in Fig. 5, the main microphone 1 is shown in a circuit having a source of E. M. F. 18, depicted as having one pole grounded; grounded circuits being generally employed on shipboard. The additional microphone 17 is shown in similar circuit having a source of E. M. F. 19, also depicted with one pole grounded. The selecting switch 3 is shown as connected in series with the microphone 1 and source of E. M. F. and has, by way of example, four poles or contacts engaged by 45 a switch arm 30 by which three loudspeakers may be separately operated or all operated simultaneously. These contacts are denoted respectively 31, 32, 33, and 34; the switch arm 30 being connected in series with the microphone.

50 From the contacts 31, 32, and 33 are led parallel conductors 41, 42, and 43 which have interposed therein respectively switches as indicated at 44, 45 and 46 for selectively connecting the parallel systems of the network. One system is shown as comprising conductors 41', 42', and 43' leading from contact poles 44', 45', and 46' that are engaged respectively by the switches 44, 45, and 46 in one position; there being another set of corresponding contact poles 54, 55, and 56 engaged in the other position. The conductors 41', 42' and 43' lead respectively to one of the poles of each of the amplifying devices 47, 48, and 49 which comprise the amplifier, shown generally at 4. From the other pole of each of these devices are led in parallel the conductors 410, 420, and 430 which lead respectively to outlets shown at 61, 71, and 81. (These may be regarded, by way of example, as located at stations 6, 7, and 8 on the ship.)

70 The outlets to which the loudspeakers are connected are shown as comprising terminals 62 and 63, 72 and 73, and 82 and 83, respectively, that are each bridged by a resistance which is 75 preferably that of the driving units 21 of the

loudspeakers attached. The terminals 63, 73, and 83 each have connections, as shown at 64, 10 74, and 84, respectively, for grounding them, in order that the circuits which actuate the loudspeakers may be completed.

5 From the contacts 54, 55, and 56 which provide for connection of the microphone to the alternative system are led the conductors 51, 52, and 53 comprising the network arranged in parallel with conductors 41', 42', and 43'. The conductors 51, 52, and 53 lead respectively to one of the poles of each of the amplifying devices 57, 58, and 59 which comprise the amplifier shown generally at 5. From the other pole each of these devices is led in parallel with the conductors 510, 520, and 530 which lead respectively to outlets 61, 71, and 81 in parallel with conductors 410, 420, and 430. Also associated with each selector switch at the microphone is master switch 65 which is preferably actuated by the key of the officer in command and has two operative positions, in one of which it connects the microphone connection in series with the selector switch 3, while in the other it engages a contact 66 for short circuiting the microphone 25 when it is desired to test the circuits, as hereinafter more fully explained.

When it is desired to operate all the loudspeakers simultaneously, the switch arm 30 is moved into engagement with contact 34, provided for this purpose, which connects at one time all the circuits to the loudspeakers in parallel but in series with the microphone. To this end, there is shown a conductor 35 leading from the contact 34 that has a branch 36 leading to conductor 41, a branch 37 leading to conductor 42, and a third branch 38 leading to conductor 43.

The circuits for actuating the loudspeakers from the additional microphone 17 are shown as comprising conductors 41^a, 42^a, and 43^a, which lead from a selector switch 3^a and are connected respectively to switches 44^a, 45^a, and 46^a which have two sets of contact poles, one of which are the terminals of the set of conductors 411, 421, and 431 which are extensions of conductors 41^a, 42^a, and 43^a; the other set serving to connect the set of conductors 511, 521, and 531 that are extensions of conductors 51, 52, and 53. The selector switch 3^a has contacts 31^a, 32^a, and 33^a which correspond to those of selector switch 3. It is from these contacts that conductors 41^a, 42^a, and 43^a lead. A contact 34^a provided to correspond to contact 34 has connections whereby it connects all the loudspeakers for actuation in parallel. A master switch 65^a likewise has two operative positions similar to that shown at 65.

By the wiring arrangement thus provided, the microphone 1 may be made to actuate the loudspeakers at outlets 61, 71, and 81 selectively by turning arm 30 to engage with contacts 31, 32, and 33, respectively, or it may be made to operate all of the loudspeakers simultaneously by moving the switch arm to engage contact 34. This actuation may be made to take place through either of the parallel systems in the network, depending on the position of switches 44, 45, and 46; the master switch 66 being, of course, in position to connect the microphone in service. Similar actuation of the loudspeakers may be had from the additional microphone 17 by moving the selector switch 3^a to engage corresponding contacts, since the selector switches are substantially identical. The amplifiers are, of course, individually adjusted so that the loudspeakers at the respective stations reproduce 75

acoustically the signals which enter the microphones with a volume of sound that is above a predetermined noise level.

The loudspeakers, as already indicated, are preferably of the character shown in my said copending application; a suitable form thereof being shown in Fig. 4, where 20 denotes the driving cone operated by a permanent driving unit 21, and 22 is the driven cone. The driving cone 10 is supported at its periphery by a ring 21 which is perforated to allow of free passage of air to and from the space between the cones. Both cones are of metal and the driven cone is either of rustproof material or has its outer face 15 painted, and if desired, a protective grating may be employed over the face of the driven cone. The speaker unit is enclosed in a damp-proof cylindrical casing 23, the back 24 of which may readily be removed for inspection by undoing holding screws 25 and the front of the casing being formed by the driven cone itself.

The available output of each loudspeaker is preferably 15 watts at least. The adjustments of the loudspeakers are such as to make it suitable for reproducing with maximum penetrating power sound frequencies between 100 and 1200 per second. Where the loudspeaker is embodied in the structure of the ship, say, in the wall of the cabin, that wall or plate may act 30 as a baffle plate around the driving and driven cones, while in the case of the boat stations, the loudspeakers, of the type described, may be embodied in a standard of each davit or in the ship's plating adjacent to each boat station.

35 A pilot light 26, which may be on the back 24 of each speaker, is provided and connected in parallel with each speaker circuit so that this circuit may be tested without operating the speaker and possibly thereby causing alarm.

40 In cases where a ship has two or more engine rooms or where different sections of a ship can be completely separated by bulkheads and water-tight doors, the loudspeaker stations according to this invention may be arranged or duplicated accordingly.

45 Since certain changes may be made in the above construction and different embodiments of the invention could be made without departing from the scope thereof, it is intended that all 50 matter contained in the above description or shown in the accompanying drawings shall be interpreted as illustrative and not in a limiting sense.

Having described my invention, what I claim 55 as new and desire to secure by Letters Patent is:

1. In a ship's signaling system, the combination with a microphone located at a control point in the ship, of an electrical network connected to said microphone, said network comprising duplicate wiring systems running throughout the ship and located some distance apart, said systems having common outlets located at selected stations in said ship, and loudspeakers of a character adapted to reproduce sound connected to 60 said outlets; said systems being adjusted to reproduce acoustically the signals entering said microphone at said loudspeakers with a volume of sound above a predetermined noise level.

2. In a ship's signaling system, the combination with a microphone located at a control point 70 in the ship, of an electrical network connected to said microphone, said network comprising duplicate wiring systems running throughout the ship and located some distance apart and each leading to common outlets located at selected

stations in the ship, an amplifier for said network located at a desired point, a selecting switch connected in said network adjacent said microphone whereby a signal may be delivered to one or more of said stations selectively at will, and loudspeakers capable of reproducing sound having a highly penetrating quality connected to each of said outlets.

3. In a ship's signaling system, the combination with a microphone located at a control point 10 in the ship, of an electrical network connected to said microphone, said network comprising duplicate wiring systems running throughout the ship provided with protecting sheathing and located some distance apart, said systems having a plurality of common outlets located at selected stations in the ship, duplicate amplifiers associated with said systems at protected points in the ship and arranged for alternate use, a selecting switch associated with said systems and disposed adjacent said microphone whereby signal energy may be sent selectively to one or more of said stations, and loudspeakers capable of reproducing sound with a highly penetrating quality connected respectively to said outlets and adjusted to reproduce signals with a volume of sound above a predetermined noise level.

4. In a ship's signaling system, the combination with a microphone located at a control point 20 in the ship, of an electrical network connected to said microphone, said network comprising duplicate wiring systems running throughout said ship and located some distance apart, said systems having a plurality of common outlets located at selected stations in the ship, loudspeakers capable of reproducing sound so as to have a highly penetrating quality connected respectively to said outlets, a pilot light associated with each of said loudspeakers, and a selecting switch associated with said network and arranged to select one or 30 more of said loudspeakers to reproduce the signal at will and provided with means for illuminating said pilot light to test the circuit.

5. In a ship's signaling system, the combination with microphones located respectively on the bridge and adjacent the binnacle, of an electrical network connected to said microphones comprising duplicate wiring systems located some distance apart and having a plurality of common outlets located at selected stations in said ship, loudspeakers capable of reproducing sound so as to have a highly penetrating quality connected to each of said outlets, and selecting switches connected in said network adjacent each of said microphones whereby one or more of said 40 loudspeakers may be selectively operated at will.

6. In a ship's signaling system of the character set forth in claim 1, the use of loudspeakers which have two independent diaphragms spaced apart by a relatively narrow distance, said diaphragms being conical in shape and having an angle at the apex which is substantially 178°.

7. In a ship's signaling system of the character set forth in claim 1, the use of loudspeakers which have two independent diaphragms spaced apart by a relatively narrow distance, said diaphragms being conical in form and made of rust-proof metal.

8. In a ship's signaling system of the character set forth in claim 1, the use of loudspeakers which have a moistureproof casing set in a wall of the ship and a rustproof diaphragm closing the front of the loudspeaker.
